Attorney

UNITED STATES PATENT OFFICE.

WILLIAM A. DOBSON, OF BRIDGEPORT, CONNECTICUT, ASSIGNOR TO UNDERWOOD ELLIOTT FISHER COMPANY, OF NEW YORK, N. Y., A CORPORATION OF DELAWARE.

TYPEWRITING MACHINE.

Application filed October 23, 1925. Serial No. 64,814.

This invention relates to the tension adjustment of the returning springs for the key-levers of typewriting machines, and more particularly to means for locking the 5 adjusting devices.

Since the keys of the machine are all fulcrumed on a common shaft, and since some of the keys are longer than the others, the touch of some of the keys is lighter than 10 that of others. One of the features of this invention relates, therefore, to means whereby the movement arising from this and other sources is overcome, and the touch of all the keys is made uniform. There is provided a 15 series of individual springs compressed between a fixed plate under the keys and the keys themselves, the springs having individual adjusting means. Each spring is borne by a stud screwed into the plate, the springs 20 and screws being staggered or arranged in echelon to correspond with the arrangement of the keys in rows and in a manner to improve the leverage of the keys.

Another feature of this invention relates to 25 means for locking the studs for the springs. For simultaneously locking all the studs, there is provided a lock-plate wide and long enough to take in all the studs, the studs being provided with flattened shanks into ob- 30 long holes in said plate. The studs are individually adjusted, and then the lock-plate is placed over the heads of the screws and is secured to the fixed plate.

Other features and advantages will here- 35 inafter appear.

In the accompanying drawings,

Figure 1 is a side view, in elevation, of a type-action to which the invention may be advantageously applied.

40 Figure 2 is a plan view of Figure 1.

Figure 3 is a fragmentary bottom view, showing the lock-plate and the stud-supporting plate, the latter being secured to the frame of the machine.

45 Figure 4 is a cross-sectional view, in elevation, showing the springs and adjusting means therefor.

This invention is illustrated as applied

to the type-action of an Underwood portable typewriting machine. Said machine has a 50 series of keys 10, key-levers 11 fulcrumed upon a common shaft 12, and means for swinging type-bars 13 when the keys are depressed. Said means may include a series of rocking members 14 fulcrumed upon a 55 common shaft 15, and are operatively connected to the key-levers by means of a pin 16 and a slot 17. The rocking members may be provided with upwardly-extending arms 18, the ends thereof having holes 19 for receiving the ends of links 20, which links are pivotally mounted at 21 upon lower extensions or short arms 22 of the type-bars 13. The key-levers are returned to their normal position, after each depression, by means of 60 65 springs 23.

Since the keys 10 are staggered as shown in Figure 2 and since the fulcrum-shaft 12 of the key-levers is the same for all the keys, it will be apparent that the longer 70 key-levers will be easier to depress, thereby making the touch of the keys uneven, which is objectionable.

For the purpose of improving this condition, the positions of the springs 23 have 75 been staggered according to the positions of the keys on the key-levers. This will improve the uneven depression of the keys some, but not enough to equalize the touch of all the keys. Each spring is therefore pro- 80 vided with individual adjusting devices, which may include a series of studs 24 threaded into a cross-plate 25, the screws being reduced in diameter at 26 for receiving a flange or washer 27. In order to 85 stiffen the cross-plate 25, which is secured to the side frame 28 of the machine at the ends only, by means of screws 29, it is proposed to build it in the form of a channel having side walls 30, which may form an 90 integral part of the cross-plate 25.

The heads of the studs 24 may have the sides flattened at 31 in order to provide means whereby the studs may be both screwed into the tapped holes and locked against rotation 95 after adjusting the tension of the spring.

To this end, there is provided a plate 32 having elongated holes 33 of a width equal to the width of the flattened portion of the studs. The plate has one hole for each 5 stud, and each hole is placed to correspond with the position of the studs in the cross-plate 25. The plate 32 may be made wide enough to fit between the side walls 30 of the cross-plate, and may be secured in place 10 by means of screws 34. The rear ends 35 of the key-levers 11 may be provided with projections 36, forming an integral part thereof for positioning the upper ends of the springs 23, said projections being in line 15 with the studs 24.

Since the key-levers 11 are provided with an open slot 37 for engagement with the fulcrum-shaft 12, it will be clear that means must be provided to prevent accidental 20 placement of said key-levers. In this invention, there is provided an angular plate having a rear side 38 and a lower side 39 and extending substantially the full width of the machine, so that the lower side will 25 prevent the removal of the key-levers. Said angular plate may be secured to the rear frame 40 of the machine by means of screws 41.

Variations may be resorted to within the 30 scope of the invention, and portions of the improvements may be used without others.

Having thus described my invention, I claim:

1. In a portable typewriting machine, in 35 combination, means for equalizing the touch of the key-levers including a series of compression springs arranged in staggered rows under the key-levers and studs having non-circular heads for adjustably backing said 40 springs, and unyielding, unitary means for locking all of said studs against accidental rotation, including a plate having non-circular openings within which said stud-heads are caged.

2. In a portable typewriting machine, in 45 combination, means for equalizing the touch of the key-levers including a series of compression springs under the key-levers, a cross-bar secured to the side frames of the 50 machine and studs screwed in said cross-bar, and means for locking said studs against accidental rotation, said last-mentioned means including flattened portions on said studs, a plate having elongated holes therein for receiving all of said flattened portions, and instrumentalities for securing said 55 plate to said cross-bar.

3. In a typewriting machine having 60 depressible key-levers fulcrumed at the rear of the machine upon a common shaft, the combination of means for holding the key-levers in their normal position, said means including a spring under each lever, the springs being arranged in a plurality of rows, a 65 cross-frame, studs screwed into said frame

and serving as a backing for said springs, said studs having downwardly-disposed heads of a non-circular cross-section, a plate having perforations for locking engagement with the heads of the studs, the perforations in the plate being placed to correspond with the position of the studs in a manner to afford the entering of all the heads into their corresponding perforations in the plate to be caged therein, thereby preventing the rotation of all the studs, and means for securing said plate against displacement. 75

4. In a portable typewriting machine having depressible key-levers and staggered 80 keys therefor, said key-levers being parallel to each other and all being fulcrumed upon a common shaft at the rear of the machine, the combination of means for equalizing the effort required to depress the keys, said 85 means including a series of springs under the key-levers and staggered to correspond to the staggered position of the keys, flattened studs in line with the springs for regulating the tension of said springs, and 90 means for simultaneously locking all the studs against rotation, said last-mentioned means including a thin, light locking plate having perforations arranged in staggered 95 relation corresponding to the stud formation for engagement with flattened portions of said studs, so that the locking plate may be simultaneously passed over all the studs, and devices for locking the locking plate against displacement. 100

5. In a typewriting machine having depressible key-levers, the combination of a U-shaped channel-plate extending under said levers between the sides of said machine, said channel-plate having its side 105 members turned down and being arranged with threaded holes through its web or top portion, one of said holes being positioned under each of said levers, studs threaded into each of said holes, a spring supported 110 on the upper end of each stud for pressing against a key-lever directly above it, a thin locking plate having a width whereby to permit it to fit snugly and compactly between the side members of such channel-plate, and means for fastening said locking plate to said channel-plate, said locking plate having a plurality of irregularly-shaped holes each arranged for registering with one of said studs, the lower-end of each of said studs being shaped or flattened to afford a means for turning said stud in said channel-plate to adjust the spring-pressure on the key-lever above it, said lower flattened end being further arranged to engage snugly in the hole of said locking plate below it to prevent accidental rotation of said stud. 115 120 125

6. In a typewriting machine, in combination, a series of key-levers, a coil-restoring 130

spring for each lever, a cross-bar having a series of studs threaded therein, each stud having an upper reduced portion and a lower flattened portion integral therewith, a bushing mounted on said reduced portion for supporting the restoring spring so that upon rotation of said studs the spring-ten-

sion for each key-lever may be individually adjusted, and means for locking the studs against accidental rotation, said means including a plate secured to the cross-bar and having elongated holes therein to receive the lower flattened stud-portions.

WILLIAM A. DOBSON.
